CLAIM

The ornamental design for an automobile tire, as shown and
described.

DESCRIPTION

FIG. 1 is a front view of an automobile tire, showing the new
design, the top plan view and the bottom plan view appear-
ing the same as the front view;
FIG. 2 is a rear view of the automobile tire;
FIG. 3 is a right side view of the automobile tire;
FIG. 4 is a left side view of the automobile tire;
FIG. 5 is a fragmentary front view, showing in enlargement
the portion of 5—5 in FIG. 1; and,
FIG. 6 is a cross-sectional view, taken on line 6—6 in FIG.
5.
